(57) **CLAIM**

We claim the ornamental design of a utility pump, as shown and described herein.

DESCRIPTION

FIG. 1 is a top perspective view of a utility pump according to some embodiments of the present invention;

FIG. 2 is a top perspective view of the utility pump in FIG. 1 rotated 180° according to some embodiments of the present invention;

FIG. 3 is a side view of the utility pump in FIG. 1 from one side according to some embodiments of the present invention; FIG. 4 is a side view of the utility pump shown in FIG. 1 from the other side according to some embodiments of the present invention;

FIG. 5 is a front view of the utility pump shown in FIG. 1 according to some embodiments of the present invention;

FIG. 6 is a back view of the utility pump shown in FIG. 1 according to some embodiments of the present invention;

FIG. 7 is a top view of the utility pump shown in FIG. 1 according to some embodiments of the present invention; and,

FIG. 8 is a bottom view of the utility pump shown in FIG. 1 according to some embodiments of the present invention.
